UNITED STATES PATENT OFFICE.

MARTIN ANDERSON HALDEEN, OF CHICAGO, ILLINOIS.

RAZOR-BLADE SHARPENER.

1,159,763.

Specification of Letters Patent.

Patented Nov. 9, 1915.

Application filed January 8, 1915. Serial No. 1,124.

To all whom it may concern:

Be it known that I, MARTIN ANDERSON HALDEEN, a citizen of the United States, residing at Chicago, in the county of Cook 5 and State of Illinois, have invented certain new and useful Improvements in Razor-Blade Sharpeners, of which the following is a specification.

This invention relates to improvements in 10 razor sharpeners and more particularly to that class designed to grind a razor blade.

One object of the invention is to provide 15 grinding rolls which engage both sides of the blade simultaneously thereby performing the sharpening operation quickly.

Another object is to provide a blade holding 20 device that may be turned completely around without removing the blade thereby permitting each face of the blade to be sharpened by each grinding roll to impart an even edge to the blade.

Another object is to provide a blade holder 25 that may be rotated and adjusted at any angle to the perpendicular desired to hold the blade in a position in which it may be honed preparatory to the sharpening operation.

With the foregoing and other objects in 30 view the invention consists in the combination and arrangement of parts to be herein-after fully described in the following specification, pointed out in the claim and illustrated in the accompanying drawings which form a part of said specification and in 35 which—

Figure 1 is a top plan view of my improved razor sharpener. Fig. 2 is an end elevation of the same. Fig. 3 is a side view. Fig. 4 is another side view of the device. 40 Fig. 5 is a longitudinal sectional view taken on line 5—5 of Fig. 1. Fig. 6 is an end view with one of the grinding rolls removed to show the blade retaining means.

Like reference characters indicate corresponding parts throughout the several views. 45

My razor sharpener comprises the grinding rolls 1, 2 mounted upon shafts 3, 4 carried by the frame 5 which frame is preferably of oblong shape and provided with the 50 handle 6. The said frame is slotted longitudinally in each side at 7, in which slotted portion the ends of the shaft 4 are disposed, to permit limited longitudinal movement of shaft 4 with respect to the frame. The shaft 55 4 is journaled in a yoke 8 arranged inside the frame 5 and supported upon guide pins

9, 9 which extend through apertures in one end of the frame and which guide pins are provided with pressure springs 10, 10 that abut the frame and yoke to place the latter member under a tension. A draw pin 11 also carried by the yoke 8 extends through an aperture in the frame 5 and is threaded as at 12 to receive the adjusting nut 13 by means of which said yoke, shaft 4 65 and grinding roll 2 may be moved longitudinally of the frame 5.

The frame 5 is formed with a pair of integral standards 14, 14 which are provided with stop pins 15 and are connected by a 70 rotary cross piece 16 one of the ends 17 of which is threaded for engagement with an adjusting nut 18 so that said cross piece may be locked in any adjusted position desired. The cross piece 16 is apertured to permit 75 passage of the lift screw 19 which is operated by means of the nut 20 and said lift screw is connected, at its lower end, with the holder plate 21 which is provided with lugs 22, 22 adapted to project through openings 80 in the adjusting plate 23 to which the keeper 24, provided with finger piece 25, is pivoted at 26.

The blade 27 to be sharpened is placed 85 against the face of the holder plate, the lugs 22, 22 extending through the usual holes in the blade; the adjusting plate 23 is then applied to the holder plate and locked in position by means of the keeper 24. It is understood, of course, that for blades not having holes for passage of the lugs 22, 22 these lugs may be dispensed with and suitable clasps or other fastening means used. The 90 blade holder, which comprises the plates 21, 23 is readily raised or lowered by means of 95 the lift screw and this screw and blade holder may be rotated together with the cross piece 16 which may be locked in any position desired by means of the nut 18. As shown in Fig. 3, dotted lines, of the 100 drawings the blade may be retained in an adjusted position in which it may be honed readily and the cross piece then released and the blade adjusted between the grinding rolls.

The shaft 3 of grinding roll 1 is provided with a handle 28 by means of which it may be rotated and this motion transmitted to the roll 2 by means of the cog wheels 29, 29 carried by the shafts 3, 4; said cog wheels 110 being provided with a dog 30, carried by one standard 14, to prevent rotation in other

than one direction. The guiding rolls are spirally grooved as at 31 to impart a longitudinal as well as a transverse grind to the blade. It will be noticed that the 5 grooves and ridges in each roll are of an even width and the rolls are set so that the grooves of the one are directly opposite the ridges of the other.

What is claimed is:—

10 A razor sharpener comprising manually operable coöperating grinding rolls mounted in a frame, standards carried by said frame, a rotary cross piece connecting said

standards, a lift screw carried by said rotary cross piece, a blade holder carried by 15 said lift screw and means associated with said rotary cross piece for locking the same in an adjusted position.

In testimony that I claim the foregoing as my own I have hereto affixed my signature 20 in the presence of two subscribing witnesses.

MARTIN ANDERSON HALDEEN.
